SECURITY SEAL FOR A MAILBAG OR THE LIKE

Sigurd M. Moberg, Orange, and George A. Lundberg,
Pompton Lakes, N.J., assignors to E. J. Brooks Company, Newark, N.J.

Filed June 26, 1974, Ser. No. 483,125

Term of patent 14 years

Int. Cl. D9—06

U.S. Cl. D9—252

Fig. 1

Fig. 2

Fig. 4

FIG. 1 is a perspective view of a security seal for a mailbag or the like embodying our new design.

FIG. 2 is a top plan view;

FIG. 3 is a right side elevational view; and

FIG. 4 is a rear elevational view.

We claim:

The ornamental design for a security seal for a mailbag or the like, substantially as shown.
